UNITED STATES PATENT OFFICE

GOTTFRIED H. BINDER, OF ORANGE, NEW JERSEY, ASSIGNOR TO ZENITHERM COMPANY, INC., OF KEARNY, NEW JERSEY, A CORPORATION OF NEW JERSEY

WALL CONSTRUCTION

Application filed January 29, 1930. Serial No. 424,197.

This invention relates to certain new and useful improvements in wall construction for buildings.

The main object is to provide a construction which will permit an efficient wall to be erected with a minimum of labor and expense and which, though light in construction, will be very strong and effectively resist the passage of sound.

10 Other objects will be apparent to anyone skilled in this art in examination of the drawings and a reading of the following description.

In the drawings—

15 Fig. 1 is a side elevation of a wall partly finished and constructed in accordance with my invention, the view being on a very much reduced scale;

Fig. 2 is a relatively enlarged cross section 20 on the line 2—2 of Fig. 1;

Fig. 3 is a perspective view of the upper end of a detail of construction;

Fig. 4 is a perspective view of the upper end of another detail of construction;

25 Fig. 5 is a horizontal section on the line 5—5 of Fig. 1;

Fig. 6 is a fragmentary view of a modification.

1 represents the floor. 2 represents an 30 overhead beam. 3—3a represent studs supported on the floor 1 and in turn supporting the overhead beam 2. In the space between the floor, overhead beam and the two studs I propose to erect the wall, and in the preferred

35 form of construction shown in the drawings I employ upright channel pieces which function to some extent as supplemental studs and in addition as means for holding filler blocks, later referred to, from lateral displacement.

40 These intermediate upright pieces may be in various forms, that is to say, one piece may be in the form of a U-shaped channel member 4, the width of the channel corresponding to the thickness of the filler block to be used.

45 Another upright piece, indicated at 5 in Fig. 3 will be seen to comprise two channelled members, similar to channel member 4, secured together back to back by any suitable means, for example, by rivets 6 or spot welds. Another upright piece 7 is shown in Fig. 4.

Before installation this piece is L-shaped in cross section and is provided with a series of bendable lugs 8 along one edge. The ends of any of these upright pieces may be provided with suitable lugs to permit said ends to be nailed to the floor 1 and overhead beam 2. One such lug is indicated at 9 in Fig. 3, the said lug being provided with one or more nail holes. The bodies of some pieces may be provided with nail holes such as 10 to permit the same to be nailed flatwise against the studs, if desired.

11—11a—11b are three sets of filler blocks arranged vertically upon one another and supported on the floor with their edges resting in the channeled members previously described so as to be held against lateral displacement.

12—13 represents layers of suitable material such as cement covering the two opposite faces of the filler blocks and upright members. 14—15 represent ornamental blocks or slabs which may be applied on the opposite surfaces of the wall and backed up by the cement layers 12—13 respectively.

I will now describe how I may erect the wall shown in Fig. 1. A channeled piece 4 is first nailed to the stud 3. The vertical series of blocks 11—11 are then put in place with their edges projecting into the channeled upright 4. A double channeled upright corresponding, for example, to the piece 5 may then be fixed in place so that the edges of the blocks 11—11 will stand in one of the channels. If, at this point in the wall a vertical

passage for a conduit is desired, as indicated at 16 in Fig. 1, a second upright member 5 may be applied between the floor and the overhead beam as shown in Figs. 1 and 5 so that there will be two empty channels facing each other to provide a metallic guide

passage whereby at any time after the wall is erected a conduit, rigid or flexible, may be pushed through the passage without danger of puncturing the wall. Next the series of blocks 11a—11a would be placed in position with one edge of each block projecting into the last mentioned double channeled member 5. Next another channeled member similar to 5 would be erected to engage and hold the

100

other ends of the blocks 11a—11a. Then another series of blocks 11b—11b would be arranged in position between the last mentioned channel member 5 and the stud 3a. 5 Previous to inserting the last series of blocks an upright member similar to 7 would be nailed to the stud 3a and after the blocks 11b—11b are in place between the uprights 5 and 7 the lugs 8 would be bent over as indicated in Figs. 1 and 2 to hold this last series of blocks securely in position. When this part of the work is done the layers of cement 12—13 may be applied to the opposite surfaces of the wall. Finally, ornamental slabs 15 may be applied to one or both of the wall surfaces. The holding lugs at the ends of the uprights may be formed in any desired manner so long as they are adapted to receive one or more nails to hold the ends of the uprights in place. In Fig. 3 I have shown the lug 9 cut away at the center so as to give clearance for the pipe 16.

As shown more particularly in Fig. 6, single channels 4—4 may be secured in position 25 back to back in spaced relation so as to provide a space or passage for a pipe, conduit or the like 16. The finished slabs such as 14 as will be seen serve to enclose the pipe or conduit within the space between the channels. By placing the channels as shown in Fig. 6, the pipe or conduit will be more accessible than if completely enclosed by the legs of the channel as shown in Fig. 5.

In accordance with my invention, substantial walls and partitions may be very 35 rapidly erected. The filler blocks may be formed of very light material such as cork-board or of wood shavings or the like held in block form by a proper binder cement. The 40 finish or ornamental slabs may be of any desired material. For example, a material formed of wood chips mixed with a magnesium oxychloride cement and compressed into board form could be used. This material 45 is comparatively light and has much the appearance of stone, but may be sawed, nailed and otherwise worked substantially the same as wood. Various shades and colors are produced by mixing desired pigments before 50 compression. Some materials, such as that above mentioned, may be nailed to the filler blocks when the filler blocks are of nailable material, but it is to be understood that the ornamental slabs may be of other material 55 and may be cemented or otherwise secured in place.

In the interest of rapidity of construction, I prefer to use preformed filler blocks and preformed ornamental finishing slabs so that 60 when the wall or the partition is erected there is little or no finishing to be done. If the walls or partitions are plastered in the usual manner, considerable time is lost in waiting for the various coats to dry and harden.

65 While the invention has been described in

considerable detail and specific embodiments set forth, it is to be understood that various other modifications and embodiments may be made within the scope of the invention as defined in the appended claims.

70

I claim:

1. A wall construction comprising a lower and upper support, spaced side supports between said upper and lower supports, two intermediate double channeled upright supports between the two side supports and arranged adjacent each other to form a protected passage, one of the channels in each of said intermediate supports facing toward said side supports, with a series of filler blocks in the spaces between the side supports and the intermediate supports, one edge of said series of blocks being supported against lateral displacement by the intermediate supports, with means on the side supports for supporting the other edge of said series of blocks against lateral displacement.

75

2. A wall construction comprising upper and lower supports, side supports, an intermediate support, filler blocks between said side supports and said intermediate support, said intermediate support being secured to said upper and lower supports and comprising two separate and parallel channel members each having a channel facing toward a side support, said channel members being spaced apart to provide a conduit housing therebetween, and facings on each side of the wall covering said channel members and said filler blocks.

80

3. A wall construction comprising upper and lower supports, side supports, an intermediate support, and filler blocks between said side supports and said intermediate support, said intermediate support comprising two parallel channel members each having a channel facing toward a side support, said channel members being secured to said upper and lower supports and being spaced apart to provide a conduit housing therebetween, said conduit housing being open on both sides of the wall, and facings on each side of the wall covering the openings in said conduit housing.
